ANTENNA

Walter Berndt, Berlin, Germany, assignor to Tele-funken Gesellschaft für Drahtlose Telegraphie m. b. H., Berlin, Germany, a corporation of Germany

Application July 18, 1936, Serial No. 91,265
In Germany August 19, 1935

3 Claims. (Cl. 250—33)

This invention relates to antennae, and particularly to antennae for obtaining reduced high angle radiation.

Various antenna arrangements have heretofore been proposed for reducing undesired radiation at high angles with respect to the horizontal. For example, it has been suggested that vertically arranged antennae having a length equal to one-half the operating wave (i. e.

$$\frac{\lambda}{2}$$

where λ represents the wave length) be used for this purpose. Also, it has been proposed to employ a central vertical antenna surrounded by other vertical antennae whose lengths are the same or greater than that of the central antenna for suppressing undesired high angle radiation. Several such known arrangements are described in German Patent No. 525,101, and in United States Patents Nos. 2,048,726 and 2,064,204.

Theoretically, the calculated directional diagram for an upright antenna whose length is $\lambda/2$, such as, for instance, a mast of iron mesh, shows a zero place at about 60° (above horizon) and between 60° and 90° a small side maximum such as represented by curve 1 in Fig. 1. In practice, it has been found that a different diagram will be obtained. This difference is due to the fact that in the usual diagram only the standing wave is taken into consideration while the traveling waves are neglected. This neglect is permissible in case of vertical wire antennas having a high surge impedance, but not in the case of self oscillating iron-mesh masts whose surge impedances are substantially lower.

A better understanding of the invention may be had by referring to the drawing, wherein:

Fig. 1 shows curves explanatory of the operation, and

Fig. 2 shows one embodiment of the invention.

The traveling wave and the standing wave on the antenna can be considered as two standing waves having a relative phase displacement as to time of 90° . The one of these waves is very similar to the original standing wave, and likewise furnishes a directional diagram having a zero place, and a small side maximum (note curve 1 in Fig. 1). The other wave with a phase displacement of 90° has a directional diagram of approximately cosine shape, as indicated by the curve 2 in Fig. 1. The amplitude of the second wave is proportional to the ratio between radiation resistance and surge impedance. In like

manner, also in the directional diagram, the maximum value of the cosine curve increases with this ratio. With high radiation resistances and low surge impedances of self-oscillating $\lambda/2$ iron masts, the radiation due to the second wave determines substantially the course of the diagram for large vertical angles, see curve 3 in Fig. 1.

In accordance with the invention, this additional radiation owing to the second wave is compensated for by an antenna arrangement oscillating in opposite phase, and likewise having a cosine-like directional diagram at least for large vertical angles, i. e., for large angles with respect to the horizontal. The current of this compensation arrangement has a time phase displacement of 180° as regards the second wave, and of 270° relative to the first wave.

The required diagram is obtained, for instance, by means of several short vertical antennas A, A arranged within a small distance about the radiating mast, see Fig. 2. The correct current and phase relations are attained by suitably feeding the antennas A, A by means of power lines or cables. The proper feed may, however, also be obtained through radiation coupling. Through proper choice of the distance between the antennas, the antenna height, and the tuning means it is always possible to produce in the vertical antennas, currents of suitable value and phase. The vertical auxiliary radiators may be freely supported from rigged masts with or without roof capacity, but they may also be constructed as wire antennas utilizing the existing tensioning ropes of the mast.

A further possibility resides in the compensation by means of horizontal antennas arranged in a ray-like fashion and fed from the center across suitable tuning means, or through the radiation field. It may be of advantage to use as a feed point a current nodal point on the mast antenna.

A combination of both antenna types resides in the use of suitable or bent wires. With proper subdivision and proper tuning, the tensioning ropes or a part thereof may alone provide the compensation.

As already stated, antenna arrangements are known in which about a central antenna, vertical radiators are placed in a circle. Furthermore, horizontal wires arranged in a ray-like fashion are likewise known. However, these arrangements serve in connection with a low central radiator, to attain a suppression of the space radiation, which the central radiator alone cannot achieve.

In the arrangement according to the invention, the suppression of the space radiation is already provided for by the high iron mast. It is only the inaccuracy in the zero place in the diagram, caused by the influence of the traveling waves, that is to be compensated for by the auxiliary antennas. The currents in the auxiliary antennas are, however, small as compared with the current in the mast. The auxiliary antennas are of short length as compared with the length of the central antenna. Their distance from the central antenna must likewise be small. It is chosen preferably below $\lambda/4$ so that a diagram will be obtained which comes as close as possible to the cosine function at large vertical angles.

What is claimed is:

1. An antenna system having, in combination, a vertical radiating element whose length is approximately one-half the length of the communication wave, and means for energizing said element whereby there is produced a traveling wave component therein, and means comprising another radiating element for producing a radiation field which is maximum at zero degrees and substantially zero at 90° with respect to the horizontal, which combines with the radiation

from said vertical radiating element to compensate for the distortion of the vertical radiation pattern by said traveling wave component.

2. An antenna system comprising a central aerial having a length substantially equal to half the length of the communication wave, and a plurality of additional shorter vertical aerials located around said central aerial on a circle whose radius is one-quarter the length of the communication wave, said central aerial and additional aerials being so energized that the radiation from said additional aerials compensates for the effect of the traveling wave component on the vertical radiation pattern of said central aerial.

3. The method of operating an antenna whose radiation pattern departs from the calculated pattern due to the effects of the traveling wave component therein, which comprises producing a radiated wave independently of said antenna of a predetermined magnitude and phase whereby it combines with the radiation from said antenna to compensate for the distortion of the vertical radiation pattern by said traveling wave component.
